UNITED STATES PATENT OFFICE.

EUGENE D. BOSWORTH AND AMOS C. STALEY, OF CHICAGO, ILLINOIS.

DUPLICATING-STAMP.

984,533.

Specification of Letters Patent. Patented Feb. 21, 1911.

Application filed April 5, 1910. Serial No. 553,651.

To all whom it may concern:

Be it known that we, EUGENE D. BOSWORTH and AMOS C. STALEY, citizens of the United States, residing at Chicago, in the county of Cook and State of Illinois, have invented certain new and useful Improvements in Duplicating-Stamp, of which the following is a specification.

Our invention relates to improvements in hand stamps, and has for one of its objects to provide a duplicating hand stamp for imprinting a signature or the like, capable of making a series of impressions, and capable of being cleaned and used to imprint other signatures or like matter.

Another object of our invention is to provide a hand stamp of such character that the user may quickly and conveniently make, adapt, and arrange the printing matter on the face of the printing stamp, and as quickly remove the printing matter therefrom and substitute therefor any other such matter as may be desired.

It frequently happens in business transactions that a signature, phrase, or other notation is required to be imprinted a large number of times on as many documents or instruments, and that a delay necessary for the construction of a rubber face stamp is not permissible. To meet such contingencies, our invention is especially valuable. And still a further object of our invention is to provide in a stamp of the character described, a matrix for holding the plastic material of which the stamp is in part composed, so constructed and arranged that it may be quickly and uniformly reduced in depth to compensate for the wearing away of the plastic substance.

Other and further objects of our invention will become apparent to persons skilled in the art from the specification taken in conjunction with the drawing, wherein—

Figure 1 is a side elevation of a hand stamp partly in section; and Fig. 2 is a plan view of the matrix showing the method of reducing its thickness.

In all of the views, the same reference characters indicate similar parts.

50 5 is an ordinary wood-turned handle, such as used generally on rubber faced stamps. Secured to the small end of the handle is a flat base plate, 6, preferably of wood or like material. A matrix, 7, for holding the gelatinous composition, 8, is made of a series of 55 relatively thin frames, such as paper, or

other suitable like material. The matrix is made by superposing one frame or lamina upon another, and gluing, or otherwise cementing, adjacent laminae together until a 60 matrix of desired thickness has been built up. The matrix, as a whole, is then, in like manner, cemented to the base plate, 6. The matrix is now filled with a suitable 65 gelatinous material, 8, capable of receiving duplicating ink and making a large number of impressions therefrom. When it is desirable to duplicate a signature for instance by making a number of impressions thereof, the signature is written with the duplicat- 70 ing ink on paper; the stamp is then firmly pressed over the signature until the sensitive surface has absorbed substantially all of the ink. The stamp is then removed and it is 75 in condition to make a large number of duplicate impressions of the said signature.

The face of the stamp may be washed in fresh water, and the signature thus removed, and it will then be ready to receive another signature or the like. In this manner the 80 stamp may be used on many occasions and from time to time for a large variety of signatures, or other such brief notations or phrases, and may be prepared for such service quickly and with very little expense 85 or inconvenience to the user.

The yielding, plastic, printing material, 8, is subject to wear. When its printing surface has been worn by use too close to the lower surface of the matrix 7, one or more 90 laminae or layers of the paper frame may be removed by the application of a penknife, 9, under one or more layers, 7, as shown in Fig. 2, and the thickness of the matrix may thus be uniformly reduced sub- 95 substantially proportional to the wear of the printing substance.

Having thus described our invention, what we claim is:

1. As an article of manufacture, a multi-copying hand stamp, consisting of a handle, a flat base plate carried thereby, printing material and an enveloping frame underlying said base plate and substantially co-extensive therewith and attached at all points 100 directly to the base plate, said frame comprising superposed separable laminae, each parallel to the base plate throughout its entire extent and each surrounding a portion 105 of the printing material.
2. As an article of manufacture, a multi-copying hand stamp, consisting of a handle, 110

a base plate secured to the bottom thereof, a frame or matrix secured directly to the under side of said base plate at all points, and constituting a solid immovable edge 5 wall, said matrix being composed of a plurality of separable parallel laminæ superposed one upon the other, and a body of gelatinous composition carried by said base plate, surrounded by and slightly protruding below 10 the matrix, the constant protrusion of said

gelatinous body being attainable by physical reduction of the depth of the matrix by successive removal of laminæ.

In testimony whereof we hereunto set our hands.

EUGENE D. BOSWORTH.
AMOS C. STALEY.

In the presence of—
W. LUM ALLEN,
MARY F. ALLEN.
